UNITED STATES PATENT OFFICE.

WILLIAM F. GEHRING, OF CHICAGO, ILLINOIS.

DISPLAY APPARATUS.

Application filed May 6, 1925. Serial No. 28,398.

My invention belongs to that general class of devices known as display apparatus, and relates particularly to a device for displaying designs, words or the like, for use whenever desired. The same is particularly convenient and applicable for use by fraternal organizations for displaying their various emblems in an impressive, ornamental, attractive and convenient manner. The invention has among its objects the production of a device of the kind described that is simple, convenient, attractive, ornamental and satisfactory, and which, as before mentioned, may be used wherever found applicable.

To this end my invention consists in the novel construction, arrangement and combination of parts herein shown and described, and more particularly pointed out in the claims.

In the drawings, wherein like reference characters indicate like or corresponding parts:

- Fig. 1 is a front elevation of my improved device and stand therefor;
  - Fig. 2 is a side elevation of the same;
  - Fig. 3 is a detailed view of the controlling mechanism therefor;
  - Fig. 4 is a front elevation of the device with the front panels removed;
  - Fig. 5 is substantially a sectional view taken on line 5—5 of Fig. 4;
  - Fig. 6 is a sectional view taken substantially on line 6—6 of Fig. 4;
  - Fig. 7 is a sectional view taken substantially on line 7—7 of Fig. 4;
  - Fig. 8 is a fragmentary section looking in the same direction as Figs. 1 and 4 and illustrating certain details of construction;
  - Fig. 9 is an enlarged fragmentary rear elevation of the improved device; and
  - Fig. 10 is an elevation of controlling mechanism employed in another form of the invention.
- Referring to the drawings, in which my device is constructed to display the emblems suitable for fraternal organizations, the device being constructed in this case in the form of a star, 1 represents the back or bottom of a casing, which is provided with sides 2 extending from the bottom 1 along its edges. The sides 2 are arranged in the form of a star having points, 3, 4, 5, 6 and 7. These sides may be secured to the bottom 55 in any suitable manner and may be made of

any number of pieces, but preferably are U-shaped in the cross-section to provide flanges 2^a which may be secured to the bottom 1 and flanges 2^b to which other parts of the apparatus may be secured. I also provide sides 9 arranged between the points of the star, the sides 9 being so dispensed in this instance that they form a pentagon. Likewise, I provide a plurality of partitions 10 extending from the bottom. The partitions 10 and the sides 2 and 9 form a series of compartments or pockets which are preferably closed by panels 19 of any suitable transparent material, such as glass.

The glass face or top may be constructed of one panel or a plurality of panels. Preferably I employ a plurality of panels 19, as shown, a panel 19 being provided for each of the pockets or compartments formed by the partitions 10 and the sides 2 and 9. The glass panels may be maintained in position in any desired manner but I prefer to provide a frame 20 secured to the flanges 2^b, the frame 20 being formed of a plurality of U-shaped members 20^a and a plurality of H-shaped members 20^b. The marginal edges of the panels 19 are inserted in the grooves of the members 20^a and 20^b.

Within each compartment I preferably place suitable illuminating means. I prefer to use electric lamps for this purpose as they may be controlled in a very simple and convenient manner. Referring particularly to Figs. 4 and 5, sockets 24 are arranged within the device, there being preferably one for each compartment, which carry lamps 25. Hand holes 13 arranged in the bottom 1 are for convenience in renewing the lamps. The hand holes 13 are normally closed by plates 13^a pivotally mounted upon the outer side of the bottom 1. As illustrated in Fig. 9, a clip 13^b is provided for each plate 13^a and provides means whereby the plate 13^a may be held in a position wherein it closes the associated hand hole 13. Holes 13^c in the bottom 1 are provided for ventilation.

In my preferred construction, I provide mechanism for independently controlling each lamp. Any preferred form of controlling switch may be employed for the purpose. I have shown in Fig. 3 a suitable switch for controlling the different lamps, the switch being adapted to independently control the lamps successively in series of three. As shown, 26 is a cable carrying conductors

27 and 29, each conductor 29 directly connects a terminal of one of the lamps 25 with one of a plurality of contacts 31 forming parts of the switch. The conductor 27 is connected in parallel with the several lamps 25 and is connected in parallel to contacts 32 forming parts of the switch. Intermediate its ends the conductor 27 is connected to any suitable source (not shown) of electrical energy, the conductor 27 comprising a plurality of pieces, one of which is secured to one terminal of said source of electrical energy and another of which is connected to the other terminal of said source of electrical energy. Switch members 33 carrying a plurality of contacts 34, 35 and 36 are slidably mounted in a casing 28 which encloses the contacts 31 and 32. Movement of the switch members 33 is controlled by stops 37 and 38. Assuming that the uppermost contacts 31 in Fig. 3 are connected with the lamps 25 in three compartments, these compartments will be successively illuminated as the corresponding rod 33 is pushed in to engage the contacts 31. First, the contact 34 closes a circuit and one of the lamps will be lighted. As the switch member 33 is pushed in farther, contact 35 will close the first circuit and contact 34 will close a second circuit. As the switch member is moved in still farther, the three contacts 31 will be operatively connected with the corresponding contacts 32 and three lamps will be lighted. The member 33 may be withdrawn, as desired, to open all of the circuits. The other members 33 may then be operated in any desired order, and combination of them operated at the same time.

40 If desired, an additional chamber or compartment may be arranged at the top of the emblem. This consists of sides 45 having a suitable bottom 46, two or more lamps 25 being mounted in this compartment. I have shown the compartment without partitions so that only one set of contacts is required. The latter compartment may be secured to the remainder of the apparatus by spring fingers 47 formed upon the sides 45 and adapted to be engaged by clips 48 secured to the sides 2 (Fig. 8). Of course, other compartments may be arranged about the emblem similar to the compartments described, in which case additional contacts and conductors may be arranged in the switch box. Upon the cover may be arranged words, mottoes, or other emblems. While I have referred to the front cover of the device being transparent, and preferably of glass, I mean that it is of such material and so constructed that the illumination of lamps will show through, lighting up the panels, which are preferably in color, but so that the lamps will not clearly show through; in other words, the panels forming the covers or

top, when colored, may be termed translucent, so that while the light comes through the source of the light is not clearly seen.

The device is particularly desirable for displaying symbols or designs in a predetermined order or sequence, and displaying advertising in the same manner, the emblems being printed or painted upon the glass panels, which panels may be colored as desired. The results are most effective and impressive. Of course, when the lamps are out practically nothing shows on the panel, at least, not enough to clearly distinguish the same. Of course, other compartments may be arranged about the emblem.

I preferably mount the improved display device upon a standard which comprises uprights 41 and 42, and a cross-bar 43. The lowermost point of the star is supported in a cradle formed by a pair of bars 44. As shown, the standard may be formed by pipes or the like secured to each other by suitable fittings.

In Fig. 10 I have shown a controlling device which is employed in another form of the invention. This device comprises a switch 50 which may be substituted for the switch above described. The switch 50 preferably comprises a plurality of suitable switch mechanisms (not shown) which are controlled by push buttons 51. Each switch mechanism is operatively connected in series with one of the lamps 25 and with a suitable source (not shown) of electrical energy. Obviously, each lamp 25 is controlled solely by its associated switch mechanism.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. In a display device of the character described including a star-shaped wall, said wall being substantially U-shaped in cross section, radially disposed partitions of substantially U-shaped cross section arranged centrally within the confines of said wall, each of said radially disposed partitions meeting said star-shaped wall at the bottom of a valley of the star, angularly disposed substantially U-shaped partitions connecting the outer ends of said radial partitions thus forming an inner and outer series of compartments, a plurality of short walls of substantially U-shaped cross section angularly disposed across each valley of the star-shaped wall thus forming a third series of compartments, a frame for holding panels

115

120

125

130

135

secured to said partitions and walls and in contact with one leg of the **U** thereof, the peripheral members of said frame being of **U**-shaped cross section to accommodate a 5 panel on one edge, and the inner members of said frame being of **H**-shaped cross section to accommodate panels on opposite edges, and a cover engaging the other leg of the **U** of said walls and partitions, said cover 10 having an inwardly turned flange on its peripheral edge.

2. In a display device of the character described including a star-shaped wall, radially disposed partitions arranged centrally 15 within the confines of said wall, each of said centrally arranged partitions meeting said star-shaped wall at the bottom of a valley of the star, angularly disposed partitions connecting the outer ends of said radial 20 partitions, thus forming an inner and outer series of compartments, a plurality of short walls angularly disposed across each valley of the star-shaped wall thus forming a third series of compartments, a cover for one side 25 of said compartments comprising a frame

and panels, said frame secured to one edge of said partitions and of said walls and in contact with flanges on said partitions and on said walls, the peripheral members of said frame being of **U**-shaped cross section to 30 accommodate a panel on one edge, the inner members of said frame being of **H**-shaped cross section to accommodate panels on opposite edges, and a cover for the other side of said compartments and in contact with 35 flanges on said partitions and on said walls, said second-named cover having openings therein for access to said compartments.

3. In a display device of the character described, a star-shaped casing, a separable 40 casing mounted between points of said star-shaped casing, clips carried by said star-shaped casing, and spring fingers carried by said separable casing, said spring fingers removably engaging said clips to retain the 45 separable casing in position between said points.

In testimony whereof, I have hereunto signed my name.

WILLIAM F. GEHRING.
